UNITED STATES PATENT OFFICE.

HENRY COHIC, OF CLEVELAND, OHIO.

UMBRELLA.

1,140,801.

Specification of Letters Patent. Patented May 25, 1915.

Application filed July 2, 1914. Serial No. 848,587.

To all whom it may concern:

Be it known that I, HENRY COHIC, a citizen of the United States, residing at Cleveland, in the county of Cuyahoga and State of Ohio, have invented certain new and useful Improvements in Umbrellas, of which the following is a specification.

This invention relates to umbrellas of the folding type, and its object is to provide a novel and improved umbrella of this type which is also self-opening.

The invention consists in a combination and arrangement of parts to be hereinafter described and claimed, and in order that the invention may be better understood, reference is had to the accompanying drawing, in which—

Figure 1 is an elevation of a fragment of the umbrella in open position, only one of the ribs and parts associated therewith being shown; Fig. 2 is an elevation showing the umbrella closed; Fig. 3 is an elevation showing the umbrella folded; Fig. 4 is an elevation, partly in section, showing the joint between one of the ribs and its stretcher; Fig. 5 is a sectional detail on the line 5—5 of Fig. 4, and Fig. 6 is a section on the line 6—6 of Fig. 1 showing the joint between the stick sections.

Referring specifically to the drawing, the stick of the umbrella is in two sections denoted at 10 and 11 respectively, the former carrying a detachable handle 12 which is coupled to the stick section by a suitable catch 13. The stick section 11 carries at its outer end a tip 14. The stick sections are foldably connected, and the tip is foldably connected to the stick section 11.

The foldable connection or joint between the stick sections 10 and 11 is made as follows: Both stick sections are hollow, and the section 10 carries a short projecting stem 15 which is screw-threaded to screw into the section 11, as shown in Fig. 6. The screw stem is secured to the section 10 by a cross pin 16, or any other suitable means. In the hollow of the section 11 is slidably mounted a retaining member 17 having a head or abutment 18 at its inner end which cooperates with a stop lug 19 in the section 11 to limit the outward travel of said member. The outer end of the retaining member is connected by a pivoted link 20 to the outer extremity of the screw stem 15. The stick sections 10 and 11 are coupled together by screwing the stem 15 into the

section 11. To uncouple the stick sections, the section 10 is rotated to back the stem 15 out of the section 11. The section 10 is then pulled away endwise from the section 11 until the link 20 is on the outside, after which the two sections may be folded alongside each other, as shown in Fig. 3. The parts 18 and 19 prevent the member 17 from being entirely withdrawn from the section 11. A foldable connection as herein described is also provided between the tip 14 and the stick section 11, the link corresponding to the link 20 being indicated at 21, and the screw stem corresponding to the screw stem 15 being indicated at 22, said stem 22 being carried by the stick section 11 to screw into the tip, which latter is made hollow and internally screw-threaded for this purpose.

Adjacent to the outer end of the stick section 11 is mounted a collar 23 to which the ribs of the umbrella are pivoted as usual. The ribs are each composed of two pivotally connected sections indicated at 24 and 25, respectively, the former being the inner section, while the latter is pivotally connected at its inner end to the collar 23. The stretchers 26 for the ribs are pivotally connected at the inner ends to the usual runner 27 which is slidable on the stick, and the latter carries the usual catches 28 for the runner. The cover, which has not been shown, is secured in the ordinary manner.

The stretcher 26 is pivotally connected to the inner end of the outer rib section 25, said end being reduced in width, as indicated at 29, to fit in a slot 30 in the outer end of the stretcher. A pin or rivet 31 passing through these parts provides the pivotal connection therebetween. The rib section 24 is connected at its outer end to the inner end of the rib section 25 by a pin or rivet 32, the outer end of the rib section 24 being slotted, as indicated at 33, to accommodate the reduced inner end 29 of the rib section 25. Both rib sections are channeled in cross-section, and the reduced inner end 29 of the rib section 25 seats partly in the channel of the rib section 24 when said rib sections are placed in alignment.

The pivot 32 of the rib sections 24 and 25 is slightly in advance or outward of the pivotal connection 31 between the stretcher 26 and the outer rib section 25, and a short distance back of said pivotal connection 31 one end of a coiled spring 34 is fastened to the stretcher, the other end of said spring

being connected to the rib section 24 adjacent to its pivotal connection with the collar 23.

The function of the springs 34 is to automatically open the umbrella as will be presently described.

The outer end of the stretcher 26, adjacent to its pivotal connection 31 with the rib section 25, has a cam-like bend 35 toward 10 the rib section 24, said bend abutting against the under side of the latter rib section when the umbrella is open, for a purpose to be hereinafter described.

Fig. 2 shows the position of the parts 15 when the umbrella is closed. The springs 34 are now under tension so that when the lower runner catch 28 is operated to release the runner 27, the latter is pulled upward and the stretchers swing outward to open 20 the ribs. The upper runner catch 28 limits the upward sliding movement of the runner, and when said catch stops the runner, the stretcher and the ribs are in full open position. The umbrella is closed in the ordinary 25 manner by pulling the runner 27 down on the stick until it is engaged by the lower runner catch 28. This downward movement of the runner stretches the opening springs 34 and places the same under sufficient tension to effect the automatic opening of the 30 umbrella hereinbefore described, when the lower runner catch 28 is operated to release the runner. By attaching the springs 34 a short distance back of the pivotal connection 31 between the rib section 25 and the stretchers 26, and locating said pivotal connection back of the pivotal connection 32 between said rib section and the rib section 24, the automatic opening of the umbrella is 35 assured, as the pivots are not in dead center positions when the umbrella is closed, and there is consequently no danger of the parts sticking or binding. The slots 33 and 30 allow the parts to fold close.

40 The umbrella is foldable from open position in the following manner: The runner 27 is advanced slightly beyond the upper runner catch 28 upon disengaging said catch, as

shown dotted in Fig. 1. This movement of the runner brings the stretchers nearer to a position at right angles to the stick than when in position to hold the ribs open, and consequently the pivots 31 move outward, with the result that the rib sections 25 swing upward about their pivots 32, as shown 55 dotted in Fig. 1. The cam surfaces 35, by their engagement with the under side of the rib sections 24, assure a flexure at the joints 32. After the rib sections are partly folded as shown dotted in Fig. 1, they are 60 folded by hand to completely folded position as shown in Fig. 3, in which position the stretchers and the rib section come close together, and the umbrella, after folding the stick as hereinbefore described, is now in 65 small compact form.

The structure is simple and devoid of complicated parts liable to get out of order, in view of which the umbrella can be cheaply manufactured, and the herein described operation is reliable, and the same is readily effected. The rib sections are in perfect alignment when the umbrella is open and the joint between the sections is smooth so that there is nothing to detract from the appearance of the umbrella. 75

I claim:

In an umbrella, a stick, a runner on the stick, sectional ribs consisting of inner and outer pivotally connected sections, the outer 80 rib section having its inner end extending back of the pivotal connection, and stretchers connected to said inner ends of the outer rib sections, the outer ends of the stretchers adjacent to their pivotal connection with the 85 outer rib sections having a cam surface for flexing the rib sections at their pivotal connection, said cam surface engaging the under side of the inner rib sections when the umbrella is open. 90

In testimony whereof I affix my signature in the presence of two witnesses.

HENRY COHIC.
